UNITED STATES PATENT OFFICE.

FRED B. CARLISLE, OF MALDEN, MASSACHUSETTS.

DESIGN FOR A TIRE.

43,453.

Specification for Design.

Patented Jan. 21, 1913.

Application filed December 27, 1911. Serial No. 668,095. Term of patent 14 years.

To all whom it may concern:

Be it known that I, FRED B. CARLISLE, a citizen of the United States, and a resident of Malden, county of Middlesex, and State of Massachusetts, have invented a new, original, and ornamental Design for Tires, of which the following is a specification.

Reference is to be had to the accompanying drawing which illustrates a perspective view of a tire showing my new design.

I claim:

The ornamental design for a tire as shown.

FRED B. CARLISLE.

Witnesses:

JOHN A. KEHLENBECK,
G. V. RASMUSSEN.
